Primary Examiner — T. Chase Nelson*Assistant Examiner* — Mark Cavana(74) *Attorney, Agent, or Firm* — Perkins Coie LLP(57) **CLAIM**

The ornamental design for an ultrasound device, as shown and described.

DESCRIPTION

FIG. 1 is top view of an ultrasound device;

FIG. 2 is a bottom view thereof;

FIG. 3 is a first side view thereof;

FIG. 4 is a second side view thereof;

FIG. 5 is a rear view thereof;

FIG. 6 is a front view thereof;

FIG. 7 is a first perspective view thereof;

FIG. 8 is an additional first perspective view thereof, with the ultrasound device display shown in an open position; and, FIG. 9 is a front perspective view thereof, with the ultrasound device display shown in an open position.

The broken lines are included for the purpose of illustrating unclaimed portions of ultrasound device and form no part of the claimed design.
